DESIGN FOR A HAT

Sylvia R. Neville, New York, N. Y.

Application March 16, 1945, Serial No. 118,519

Term of patent 7 years

(Cl. D3—13)

To all whom it may concern:

Be it known that I, Sylvia R. Neville, a citizen of the United States of America, residing in New York city, county of New York, and State of New York, have invented a new, original, and ornamental Design for a Hat, of which the following is a specification, reference being had to the accompanying drawing, forming part thereof.

Fig. 1 is a front perspective view of a hat showing my new design.

Fig. 2 is a rear view thereof.

Fig. 3 is a front perspective view of the hat shown in Fig. 1 in undraped position.

Fig. 4 is a rear view thereof.

I claim:

The ornamental design for a hat, substantially as shown.

SYLVIA R. NEVILLE.
